UNITED STATES PATENT OFFICE

126,746

DESIGN FOR EMBROIDERED LACE TRIMMING OR SIMILAR ARTICLE

Robert Koenig, Hasbrouck Heights, N. J.

Application March 3, 1941, Serial No. 99,292

Term of patent 3½ years

To all whom it may concern:

Be it known that I, Robert Koenig, a citizen of the United States, residing at Hasbrouck Heights, Bergen County, and State of New Jersey, have invented a new, original, and ornamental Design for an Embroidered Lace Trimming or Similar Article, of which the following is a specification, reference being had to the accompanying drawing, forming part thereof, wherein the figure is a plan view of an embroidered lace trimming or similar article, showing my new design.

I claim:

The ornamental design for an embroidered lace trimming or similar article, substantially as shown.

ROBERT KOENIG.
